CARBURETOR

Application filed August 10, 1925. Serial No. 49,244.

This invention relates to carburetors for internal combustion engines.

It is an object of the invention to provide a carburetor having a plurality of mixing 5 passages and having fuel openings discharging separately into said passages and to provide for successively bringing said passages and fuel openings into use by travel of a common control element.

10 Another object is to provide a carburetor having a mixing chamber of Venturi shape with one passage approaching the neck of the venturi and two passages leading from said neck, and having separate provision for 15 delivering fuel at the neck of the venturi into the two last mentioned passages, and further having a common provision for controlling a mixture flow through said passages.

Still another object is to provide a carburetor in which the usual float control for the fuel will be replaced by a valve responding to the pressure drop within the mixture passage of the carburetor when the engine is running.

20 A still further object is to provide a carburetor having a dual provision for continuously producing an explosive mixture and having a control member movable to gradually increase the flow through one of said 25 passages until the same is open to its full capacity, and further movable to provide for higher speeds by gradual uncovering of the said second passage.

These and various other objects will be apparent from the following description wherein reference is made to the accompanying drawing illustrating a preferred embodiment of my invention.

Figure 1 is a view in vertical sectional elevation of the improved carburetor.

Figure 2 is a sectional view taken upon the line 2—2 of Figure 1, and primarily disclosing the mixture control throttle.

Figure 3 is a horizontal sectional view 45 taken upon the line 3—3 of Figure 1.

Figure 4 is a vertical sectional view taken upon the line 4—4 of Figure 3.

In these views the reference character 1 designates a mixing chamber which at one 50 end is open to the atmosphere as indicated at

2 while its other extremity is adapted to be connected to the intake manifold 3 of an internal combustion engine. Within the intake end of said chamber, a suitable throttle 4 is pivotally mounted. At the outlet side 55 of its neck portion 5, a partition 6 produces separate flaring passages 7 and 8, both leading from the neck portion 5 of said chamber.

9 designates a valve casing which projects integrally upward from the central portion 60 of the mixing chamber 1. A pair of needle valves 10 are vertically arranged in chambers 11 of the casing 9 to separately control a discharge of fuel from said chambers through port 12 into the neck portion of the 65 mixing chamber, said port as best seen in Figure 4, opening respectively into the passages 7 and 8 substantially at their communication with the approach portion of the mixing chamber. The needle valves 10 have their 70 upper portions threaded into the casing 9 and provided with milled adjusting head 13, as is common practice. 14 designates a pair of small pistons which are adapted to reciprocate in cylindrical bores 15 in the casing 9, the upper portion of said bores having communication by way of ports 16 with the chambers 11. Said pistons carry upon their lower ends 75 needle valves 17 which, in the lower limiting positions of the pistons, close fuel outlets 80 opening into the lower end of the bores 15 from a fuel passage 18 to which fuel is supplied by a pipe 19. Each of the pistons 14, when raised, uncovers a port 20 through 85 which fuel may discharge from the lower portion of the bore 15 into the adjacent chamber 11.

The mixture passages 7 and 8 are controlled in common by a shutter 21 pivoted at 22 within a chamber 23 upon the outlet end of the 90 mixing chamber, said chamber having a removable cover 24. The pivot 22 of said shutter carries an actuating arm 25 from which a control rod 26 leads to any desired point of control.

95 In the operation of the described invention, the quantity of mixture delivered to the manifold 3 is controlled by the shutter 21, the latter being shown in Figure 2 fully open in full lines and in closed position in 100

dash lines. As said shutter is actuated from the latter to the former position, the passage 7 is first progressively uncovered, the flow thus established being ordinarily adequate for operation for slow or moderate speeds. 5 When relatively high speed operation is desired, the quantity of mixture delivered to the manifold 3 is still further increased by a continued opening actuation of the shutter 21, whereby the passage 8 is gradually uncovered. Thus it is seen that the control member 21 acts first to regulate the flow through one of two fuel mixing passages and when the full capacity thereof is reached, the continued opening movement of said control member progressively supplements the first mentioned passage by the capacity of the second passage. 10 15

The pistons 14 are adapted to raise responsive to engine suction acting in this mixing chamber and transmitted to the bores 15 by way of the port 12 chamber 11 and port 16.

Raising of either piston 14 unseats the needle valve carried thereby, and permits a fuel flow from the pipe 19 by way of the passage 18 into the lower end of the corresponding port 15 and from the latter by way of port 20, chambers 11 and port 12 to the mixing chamber. The pistons 14 are sufficiently heavy to drop of their own weight when suction above said pistons stops, thus causing the needle valve 17 to cut off the fuel flow from the pipe 19.

An important advantage secured by the described invention is the elimination of float controlled fuel valves and the uncertainty of their operation.

By the provision of the dual fuel openings discharging into the mixing chamber and dual mixture passages respectively supplied with fuel by said openings, there is insured a proper regulation of the fuel supply to the intake manifold under all conditions of operation.

By successively uncovering the mixture passages, one for comparatively low speed operation, and the other for relatively high speeds the size of the passages are properly in proportion to the amount of fuel which said passages are required to deliver. This is not true of the ordinary carburetor which delivers its mixture through the same passage regardless of the quantity of such fuel. Because of the elimination of a float chamber, the described carburetor may be considerably more compact than such constructions as are now generally used.

From the foregoing it becomes evident that the device is very simple and efficient and provides a device which accomplishes the objects described.

While it will be apparent that the illustrated embodiment of my invention herein disclosed is well calculated to adequately fulfill the objects and advantages primarily stated,

it is to be understood that the invention is susceptible to variation, modification and change within the spirit and scope of the subjoined claims.

What I claim is:

1. A carburetor comprising a mixing chamber, a valve chamber having an outlet to the mixing chamber, a cylinder, a fuel supply passage having a fuel delivery connection with one end portion of said cylinder, means establishing a fuel delivery connection from said end portion of the cylinder to said valve chamber, a suction transmitting passage from said valve chamber to the other end portion of said cylinder, a piston reciprocatory in the cylinder between its end portions, a valve member carried by said piston and controlling said fuel delivery connection, and a valve member in said valve chamber controlling the outlet of said chamber to the mixing chamber. 70 75 80 85

2. A carburetor comprising a mixing chamber, a fuel feed chamber, and a regulating valve chamber, a suction-responsive member in the fuel feed chamber, means for delivering fuel to said feed chamber at one side of said suction-responsive member, means for delivering fuel from said feed chamber at said side of the suction responsive member to the valve chamber, a suction-transmitting connection from the valve chamber opening into said feed chamber at the other side of said suction-responsive member, an element carried by said suction-responsive member exercising control of the fuel delivery to said feed chamber, means establishing a fuel delivery and suction-transmitting connection to the mixing chamber from said valve chamber, and a regulating valve member in said chamber controlling said connection. 90 95 100 105

In witness whereof I hereunto set my hand.

ORVILLE Z. FRAZIER.
